UNITED STATES PATENT OFFICE.

PETER MCQUEENEY, OF EAST AKRON, OHIO, ASSIGNOR OF ONE-HALF TO
CORNELIUS MCQUEENEY, OF CLINTON, MISSOURI.

COMBINED WALL-PAPER CLAMP AND BRUSH.

SPECIFICATION forming part of Letters Patent No. 451,879, dated May 5, 1891.

Application filed September 17, 1890. Serial No. 365,241. (No model.)

To all whom it may concern:

Be it known that I, PETER MCQUEENEY, a citizen of the United States, residing at East Akron, in the county of Summit and State of Ohio, have invented certain new and useful Improvements in Combined Wall-Paper Clamps and Brushes; and I do hereby declare that the following is a full, clear, and exact description of the same, reference being had to the annexed drawings, making part of this specification, and to the letters and figures of reference marked thereon, in which—

Figure 1 is an end view of the brush-frame, showing its handle properly located. Fig. 2 is a view of the clamp and brush, showing a strip or section of wall-paper properly attached thereto and showing the corner-clamp properly attached. Fig. 3 is a view of the brush and clamp, showing the corner-clamp removed. Fig. 4 is a view of a portion of the brush-clamp, showing the corner-clamp attached thereto. Fig. 5 is a view of a portion of the corner-clamp, showing the same enlarged. Fig. 6 is a view showing the locking mechanism for the retaining-bar. Fig. 7 is a transverse section of the brush-frame and brush, showing the handle properly located. Fig. 8 is an end view showing the device 30 turned in proper position to brush or smooth a strip of wall-paper.

The present invention has relation to combined wall-paper clamps and brushes; and it consists in the different parts and combination of parts hereinafter described, and particularly pointed out in the claims.

Similar letters of reference indicate corresponding parts in all the figures of the drawings.

In the accompanying drawings, A represents the main bar, to which is securely attached in any convenient and well-known manner the handle a. To the bar A is journaled the rock-bar B, which bar extends nearly to the ends of the bar A. The ends of the rock-bar B are bent or curved, as illustrated in Figs. 2, 3, and 4, and are so bent for the purpose hereinafter described. To the rock-bar B is securely attached in any convenient and well-known manner the arm b, and to the free end of this arm b is attached

the hook b' or its equivalent, to which hook is attached the wire or rod C, which wire or rod extends to the lever D, to which lever said wire or rod C is attached. To the rock-bar B are securely attached the arms o, and to the free ends of said arms is attached the clamping-bar d, said clamping-bar being so adjusted that its clamping-edge will come in contact with the groove d' in the bar A, and, in conjunction therewith, operating to securely clamp the end of a strip of wall-paper between the clamping-bar d and the groove d'. To the main bar A are attached the brush-supports E, which supports are located substantially as illustrated in Fig. 2. To the brush-supports E is securely attached the brush-bar F.

For the purpose of causing the brush to spread the wall-paper, said brush is formed rounding, as shown in Fig. 3, thereby causing the center of the brush to bear or press against the wall-paper in advance of the ends of said brush.

For the purpose of providing a means of placing a strip of wall-paper in the corners of a room, I provide the following instrumentalities: H is a bar detachably pivoted to the main bar A by means of hooks and eyes e, as in Fig. 4. To the bar H is journaled the rock-bar H', said rock-bar being provided with arms f extending therefrom, to the free ends of which arms f is attached the clamping-bar g. Attached to the bar H is a spring h, the free end of which is in engagement with an arm h', extending from the rock-bar H', by which means the clamping-bar g is held out of engagement with the bar H, as in Fig. 5.

For the purpose of holding the clamping-bar d up and out of the way of the bar A, the 90 detent I is provided, and is pivoted to the block K, and for the purpose of causing said detent to engage the arm b, the spring k is provided, which spring causes the detent I to be pressed, so as to engage the arm b, as illustrated in Fig. 6.

When it is desired to attach a strip of wall-paper to the clamp proper, which strip is calculated to be placed in a corner of a room, the bar H, together with its different attachments, is connected to the end of the bar A and placed in line with said bar A, at which

time the clamping-bars *d* and *g* are elevated, and the end of the wall-paper placed between said clamping-bars and the bars *A* and *H*, when said clamping-bars are released by detaching the detent *I* from the arm *b* and disengaging the spring *h* from the arm *h'*, thereby securely clamping the end of the strip of wall-paper.

For the purpose of holding a portion of a strip of wall-paper substantially at right angles to the remaining portion thereof, the bar *H* is turned at right angles to the bar *A*, and locked in that position by means of the catch *k'* engaging the projection *k*², as in Fig. 2. When a strip of wall-paper has been elevated to the desired height, the handle *m'* is pressed downward, thereby elevating the clamping-bar *d* by means of the wire or rod *C*, and the arm *b*, at which time the extension *m* of the rock-bar *B* engages the arm *n'* on the rock-bar *H'* and elevates the clamping-bar *g*.

For the purpose of securely holding the clamping-bars *d* and *g*, the springs *K'* are provided, and are located substantially as shown in Figs. 2, 3, 4, and 5.

For the purpose of temporarily holding the wall-paper away from the wall for the purpose of matching the strips thereof the spring-arms *L* are provided, which arms are attached to the rock-bars *B* and *H'* and their free ends bent or curved, so as to extend a short distance beyond or back of the bars *A* and *H*.

When it is desired to brush or smooth a strip of wall-paper after said strip has been attached to a wall the device is turned so as to bring the brush *G* against said strip.

It will be understood that as the brush *G* is pressed against the strip of wall-paper the springs *L* will be forced or pressed backward, thereby permitting the brush *G* to properly seat itself against said strip. It will be understood that the spring *L* is not attached to the clamping-bar *d*, but may be notched or recessed into said clamping-bar *d*, if desired, or may pass directly over said clamping-bar *d*, thereby leaving the springs *L* free to move back out of the way of the brush *G* when said brush is applied to a strip of wall-paper. It

will also be understood that when the brush *G* is used that the bar *H*, together with its different attachments, should be removed from the main bar *A*. I provide hooks at each end of the bar *H* and also eyes at each end of the bar *A*, or vice versa, so that the bar *H*, together with its different attachments, can be attached at either end of the bar *A*.

Having fully described my invention, what I claim as new, and desire to secure by Letters Patent, is—

1. The combination of the bar *A*, provided with the handle *a*, the rock-bar *B*, provided with the arm *b*, the detent *I*, the spring *k*, the arms *o*, attached to the rock-bar *B*, the clamping-bar *d*, and the spring *K'*, substantially as and for the purpose specified. 60

2. The combination of the bar *A*, provided with the handle *a* and the supports *E*, the brush-bar *F*, the brush *G*, and the springs *L*, substantially as and for the purpose specified. 65

3. The combination of the bar *A*, having journaled thereto the rock-bar *B*, provided with the curved extensions *m*, the bar *H*, hinged to the bar *A*, the rock-bar *H'*, arms *f*, extending therefrom, the clamping-bar *g*, attached to the free ends of the arms *f*, the arm *h'*, extending from the rock-bar *H'*, the spring *h*, acting thereon, the projection *k*², and catch *k'*, substantially as described. 70

4. The combination of the main bar *A* and the bar *H*, removably hinged to the bar *A*, and means for holding the bar *H* substantially at right angles to the bar *A*, substantially as and for the purpose set forth. 80

5. The combination of the bar *A*, having journaled thereto the rock-bar *B*, the arm *b*, the hook *b'*, the wire or rod *C*, the lever *D*, the handle *m'*, and the clamping-bar *d*, substantially as and for the purpose specified. 85

In testimony that I claim the above I have hereunto subscribed my name in the presence of two witnesses. 90

PETER MCQUEENEY.
